UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,361,885.

Specification of Letters Patent. Patented Dec. 14, 1920.

Application filed December 8, 1917. Serial No. 208,280.

To all whom it may concern:

Be it known that I, TALBOT G. MARTIN, a citizen of the United States of America, and a resident of Chicago, county of Cook, 5 State of Illinois, have invented certain new and useful Improvements in Automatic Telephone Systems, of which the following is a specification.

My invention relates in general to automatic telephone systems and more specifically to such systems as comprise a main exchange and one or more branch exchanges.

In my prior application, Serial No. 79,622, issued as Patent No. 1,289,854, Dec. 31, 1918, 15 I have shown an improved trunk circuit for use between a sub-exchange and a main exchange and making more practical, the use of sub-exchanges in a system comprising polystation lines.

20 This invention is in the nature of an improvement on said prior application and in addition to the features shown therein, I have provided means, whereby when a subscriber of the branch exchange calls another subscriber in a distant office, an increased flow of current will be established through his line circuit to render his talking equipment more efficient and to give a better quality to the speech over long lines.

30 The principal object of my invention is therefore to provide a simple and efficient apparatus in connection with sub-exchange trunks which is made effective to increase the battery feed to the calling subscriber's telephone when connection is extended to a subscriber in a distant exchange and which apparatus operates only to complete a holding circuit for the individual switch of the calling station when a reverting call is set up.

40 Further objects and the manner of attaining them will be hereinafter more fully explained, reference being had to the accompanying drawing which shows a connection established from a subscriber in a branch exchange to a called line in the main exchange in a system embodying the principles of my invention.

In systems of the above character the subscribers' lines terminating in a branch exchange may each be provided with individual line switches which have access to a group of outgoing trunk lines extending to the main exchange and terminating in selector switches thereat. When a calling subscriber at a branch exchange lifts his re-

ceiver to initiate a call, his line is at once connected through to a selector switch at the main exchange through the medium of his individual switch and an idle outgoing trunk line. Connector switches are provided at 60 the sub-exchange for connecting with called lines therein and are accessible to selector switches in the main exchange over a second group of trunk lines.

Referring now to the figure of the drawing, I have shown a sub-station A, which may be of the general type of substations shown in British patent to T. G. Martin No. 1419 of 1910. It consists of a transmitter 2, receiver 3, receiver hook 4, ringer 5, and condenser 6. Being an automatic substation it is also provided with a pair of impulse springs 7 and 8 which are controlled through the medium of the usual finger hole dial and calling device mechanism (not shown) to 75 send out impulses over the line conductors 9 and 10 to operate the automatic switches. As the substation may be of the polystation type, a number of other similar stations may be bridged across the line conductors 9 and 10 in multiple with the substation A, each having a ringer similar to the ringer 5 which will be tuned to respond to alternating currents of different frequencies.

The line conductors 9 and 10 terminate 85 at the sub-exchange in the individual rotary line switch C which is of the general type of line switch shown in U. S. Letters Patent No. 1,186,471, granted June 6, 1916 to John Erickson. Between the local and main exchanges are a number of trunk lines similar 90 to that shown at D which lead from the banks of the individual line switches and terminate at the main exchange in selector switches of the well known Strowger type 95 one of which I have shown at E. Each trunk line leading to the main exchange is provided at the sub-exchange with a set of relays, one set of which is shown at D and which comprises a slow relay 22 connected in series with the conductor 20 and shunted by a condenser, and an electropolarized relay 23 having one winding connected in series with the other trunk conductor 21 and also shunted by a condenser. The relay 24 is 100 provided for maintaining a holding circuit for the line switch C and for closing the circuit of the polarizing winding of the relay 23. A relay 25 is also provided and is controlled by the relay 23 to cut the double 110

wound coil 26 across the talking conductors. The relay 27 is used at times to open the circuit of the relay 25. The selector is operated by impulses to pick out an idle connector switch similar to connector H of which only the essential parts have been shown and which may then be operated to connect with the called line.

The operation of the apparatus in extending a connection from the branch to the main exchange is as follows: When the subscriber A removes his receiver he closes an energizing circuit for the line relay 11 of the line switch C which extends from ground G', back contact of the lower springs of relay 12, line conductors 10 and 9 and substation A, back contact of the upper springs of relay 12, and through the relay 11 to battery. Relay 11, upon energizing over this circuit, attracts its armatures to ground the private normal from ground G² and to prepare a circuit for the rotary magnet 13 at the upper springs. Assuming now that the wipers of the line switch C are at this time resting in engagement with contacts leading to a busy trunk line, then as soon as line relay 11 attracts its armatures, current will flow from ground from some other occupying switch (not shown), over the private wiper 16, springs 17 and 18, springs 19, and through the rotary magnet 13 to battery. The rotary magnet will therefore operate to advance the wipers 14, 15 and 16 to terminals leading to another trunk line and will interrupt its own circuit in a well known manner. This operation of the rotary magnet will continue until an idle trunk line is reached, in which case there will be no ground applied to the wiper 16 and the circuit of the rotary magnet 13 will be opened. It will be observed that while the switch C was rotating the switching relay 12 was short-circuited through ground over wiper 16; as soon as this ground is removed therefore the said relay 12 will energize in series with the rotary magnet 13 from ground G² thereby disconnecting the line relay 11 and ground G' from the line conductors 9 and 10 and switching said conductors through to the trunk line conductors 20 and 21 which lead to the main exchange. The relay 12, upon energizing, also switches its own holding circuit from the ground G², at the springs of line relay 11 to the private wiper 16 which is supplied with ground from the trunk relays D as soon as the line is cut through in a manner to be explained.

As soon as the switching relay 12 cuts the talking conductors 9 and 10 through, an energizing circuit is closed for the line relay 50 of the selector switch E which is individual to said trunk line 20-21 at the main exchange over the following path: 65 from ground through lower winding of

relay 50 to the trunk conductor 21, through the left hand winding of relay 23, and through the substation A and back over the trunk conductor 20 through the slow relay 22 and thence through upper winding of 70 said line relay to battery. The relay 22 will energize over this circuit and close a circuit for the slow acting relay 24 from ground, through springs 34 and 35 and relay 24 to battery. Relay 24 will now energize and 75 attract its armature 43 to ground the release trunk to maintain the switching relay 12 of line switch C energized and will also close a circuit for the right hand polarizing winding of the relay 23. The relay 23 will 80 not energize at this time due to the fact that current is flowing in opposite directions through its two windings over the above traced circuits.

The calling subscriber may now operate 85 his calling device for the first digit of the called number, thereby separating the springs 7 and 8 a predetermined number of times to open the circuit of the line relay 50 of the selector E which operates in response to these interruptions to step the wipers 28, 29 and 30 up to some level in the bank in which are located contacts leading to connector switches which have access to the desired subscriber. Although the circuits of the two series relays 22 and 23 are opened each time an impulse is delivered over the trunk 20-21, this will have no effect upon the armatures of said relays; relay 22 being slow acting, will not allow its armature to fall back, while the right hand winding of relay 23 is not strong enough to attract the armature alone. As soon as the impulses of the first digit cease the selector E will rotate automatically in the 95 usual manner to pick out an idle trunk line leading in this case to a connector H. When the wipers 28 and 30 connect with the connector H a circuit is closed for the line relay 31, which extends from ground through the lower winding of said relay, wiper 30, and through the substation A over the circuit previously traced for the line relay 50 of selector E and back through the wiper 28 and the upper winding of relay 31 to 100 battery.

The calling subscriber then operates the connector H through the medium of his calling device in a manner well known in connection with switches of the Strowger type, 110 to test and connect with the called substation. As soon as the called subscriber removes his receiver in response to the operation of his signal, a circuit will be closed for the back bridge relay 33 in the usual manner over a circuit including the two sides of the called subscriber's line in series. The relay 33, upon energizing, attracts its armatures to reverse the connections of the line relay 31 to the talking conductors, 115 120 125 130

thereby reversing the flow of current over the trunk lines by means of which the connection has been extended, and through the calling substation.

5 The reversal of current causes the two windings of the relay 23 to assist each other and to therefore attract the armature 34 to close a circuit for the relay 25. The circuit for the relay 25 may be traced from ground 10 G³, through springs 36 and 37, springs 35 and 34, and through the relay 25 to battery. The relay 22 being slow acting, does not release its armature when this reversal of current takes place. The relay 25, upon energizing, bridges the double wound coil 26 across the talking conductors 20 and 21 in parallel with the line relay 31 of the connector H, thereby increasing the current which flows over said trunk conductors and 15 20 the calling subscriber's line in series.

Let us assume now that the calling subscriber at A desires to call another subscriber on his own line, in which case, as pointed out in my said prior application, he 25 will operate his line switch C in the usual manner to select an idle trunk such as 20-21 leading to a selector E in the manner before pointed out. The selector E will then be operated to select an idle ring back switch 30 such as that shown at H and which may be connected to the contacts 38, 39 and 40 which are accessible to selector E. The ring back switch shown at H and the ringing equipment M are shown and described in my 35 prior application.

After the subscriber has dialed the special number required he will then hang up his receiver, thereby causing the ring back switch to operate to ring both calling and 40 called subscribers' bells alternately. It will be noticed that when the calling subscriber hangs up his receiver and while the ringing is taking place, that the direct current circuit of relay 22 and also of the left hand 45 winding of relay 23 are broken, while current from the ringing generators flows therethrough. Means has therefore been provided for maintaining the holding circuit for the switching relay 12 of line switch C 50 closed to prevent the release of the connection.

A short time after the receiver is hung up at the calling subscriber's station, the relay 22 of trunk relays D will deenergize and 55 open the circuit of the relay 24 and close a circuit at the springs 34 and 41 for the high resistance relay 27, which circuit extends over the lower talking conductor to battery through the low resistance relay 110 60 in the ring back switch. The relay 27 will immediately energize over this circuit to close another circuit through springs 36 and 42 for the relay 24 and to also open a point in the circuit of the relay 25. It will be 65 seen therefore that the relay 24 will not have

time to deenergize but will maintain the circuit closed for the relay 12 of line switch C. Should the relay 23 vibrate with ringing current and operate to attract its armature 34 it will be seen that the circuit for the 70 relay 25 will not be closed, due to the fact that the relay 27 maintains one point in said circuit open at the springs 36 and 37. As soon as the called subscriber answers, the circuit for the relay 22 will again be closed 75 and conversation will take place in the usual manner and without the increased battery being applied to the talking circuit.

When the conversation is completed, the 80 subscribers at both calling and called substations will replace their receivers, thereby opening the circuits of the line relay 100 of the ring back switch and causing the release of the ring back switch and of the selector switch in the usual manner. In this case the 85 relay 22 of trunk relays D will again fall back and open the circuit of the relay 24. The falling back of the relay 22 does not at this time cause the relay 27 to energize, due to the fact that there is no battery on the 90 trunk conductor 21 at the ring back or first selector, which switches having both released. The relay 24 will therefore fall back after a short interval and open the circuit of the switching relay 12 of the line 95 switch C and therefore cause the apparatus to be restored to normal.

It will be seen from the foregoing that I have provided a simple and highly efficient means whereby a polystation subscriber 100 whose line terminates in a branch exchange, may call another subscriber in a distant exchange and whereby in such a connection an increased flow of battery will be supplied to his transmitter in order to increase the 105 talking efficiency thereof. Also whereby such a means may be utilized to extend a connection to a ring back switch at the main exchange over a two conductor trunk line for calling another subscriber on the same 110 line and which will operate in a manner permitting said calling subscriber to hang up his receiver to allow the called subscriber to be signaled and whereby the connection will not be released.

While I have illustrated and described one embodiment of my invention in connection with a specific type of apparatus it will be understood that I do not wish to limit myself to the exact form shown herein, but 120 that my invention may be applied to various uses and types of apparatus. I desire therefore to include and have protected by Letters Patent all forms and modifications of my invention which may come within the 125 scope of the appended claims.

What I claim as my invention is:

1. In a telephone system, a main exchange, a branch exchange, subscribers in each exchange, means whereby a subscriber 130

- in the branch exchange may call another subscriber in the branch exchange or a subscriber in the main exchange, means for supplying talking current to the calling subscriber, means for increasing said current supply when a subscriber in the main exchange is called and means for preventing said increase of current when another subscriber in the branch exchange is called.
- 10 2. In a telephone system, polystation lines, other lines, means whereby one of the subscribers on a polystation line may call a subscriber on his own line or one of the subscribers on one of said other lines, means for supplying current for talking purposes to the calling subscriber's line, means for increasing the supply of current to said line when a call is made to one of said other lines, and means for preventing the increase of current supply when the call is made to another subscriber on the same line.
- 15 3. In a telephone system, a party line, a trunk line, an automatic switch for connecting the two, a ring back switch, another line, means for extending said connection to said ring back switch to signal another station on the same line, or for extending the connection to said other line, means for supplying talking battery current to said line in either case, a relay in said trunk line for maintaining said automatic switch in operated position independent of said party line when the connection is extended to said ring back switch, another relay for increasing the supply of talking current to said party line when connection is extended to said other line.
- 20 4. In a telephone system, a party line, a trunk line, an automatic switch for connecting the two, a ring back switch, another line, means for extending said connection to said ring back switch to signal another station on the same line, or for extending the connection to said other line, means for supplying talking battery current to said line in either case, a relay in said trunk line for maintaining said automatic switch in operated position independent of said party line when the connection is extended to said ring back switch, another relay for increasing the supply of talking current to said party line when connection is extended to said other line, and means for preventing the operation of said last relay when the connection is extended to said ring back switch.
- 25 5. In a telephone system, a party line, a trunk line, an automatic switch for connecting the two, means whereby a subscriber on said party line may extend a call over said trunk line, either to another subscriber on said party line or to a subscriber on another line, means for supplying current for talking purposes to said line in either case, a relay in series with said trunk line for maintaining said automatic switch in operated position independent of said party line, another relay in said trunk line for increasing the talking current supply to said party line, and means for preventing the operation of said last relay when connection is extended to a subscriber on the same line.

ent of said party line, another relay in said trunk line for increasing the talking current supply to said party line, and means for preventing the operation of said last relay when connection is extended to a subscriber on the 70 same line.

6. In a telephone system, a party line, a trunk line, an automatic switch for connecting the two, means whereby a subscriber on said party line may extend a call over said 75 trunk line, either to another subscriber on said party line or to a subscriber on another line, means for supplying current for talking purposes to said line in either case, a relay in series with said trunk line for maintaining said automatic switch in operated 80 position independent of said party line, another relay in said trunk line for increasing the talking current supply to said party line, and means for preventing the operation of said last relay when connection is extended to 85 a subscriber on the same line.

7. In a telephone system, a party line, a trunk line, an automatic switch for connecting the two, means whereby a subscriber on 90 said party line may extend a call over said trunk line, either to another subscriber on said party line or to a subscriber on another line, means for supplying current for talking purposes to said line in either case, a relay in 95 series with said trunk line for maintaining said automatic switch in operated position independent of said party line, another relay in series with said trunk line for increasing the talking current supply to said party line, and means for preventing the operation of 100 said last relay when connection is extended to a subscriber on the same line.

8. In a telephone system, a party line, a trunk line, an automatic switch for connecting the two, a ring back switch, another line, means whereby a subscriber on said party line may either extend the connection to said ring back switch to thereby project ringing current back over said trunk line to signal 105 another subscriber on the same line, or to said other line, means for supplying current for talking purposes to said party line, a relay in said trunk line adapted to increase the supply of talking current to said party 110 line when the connection is extended to said other line, another relay in said trunk line, said last relay adapted to render said first relay inoperative when connection is extended to said ring back switch.

9. In a telephone system, a party line, a trunk line, an automatic switch for connecting the two, a ring back switch, another line, means whereby a subscriber on said party line may either extend the connection to said ring back switch to thereby project ringing current back over said trunk line to signal another subscriber on the same line, or to said other line, means for supplying current for talking purposes to said party line, a 115 120 125 130

relay in said trunk line adapted to increase the supply of talking current to said party line when the connection is extended to said other line, another relay in said trunk line, 5 said last relay adapted to render said first relay inoperative when connection is extended to said ring back switch, and means controlled by said first relay for maintaining said automatic switch operated independent of said party line.

10 10. In a telephone system, a party line, a trunk line, an automatic switch for connecting the two, a ring back switch, another line, means whereby a subscriber on said 15 party line may either extend the connection to said ring back switch to thereby project ringing current back over said trunk line to signal another subscriber on the same line, or to said other line, means for supplying 20 current for talking purposes to said party line, a relay in said trunk line adapted to increase the supply of talking current to said party line when the connection is extended to said other line, another relay in said trunk 25 line, said last relay adapted to render said first relay inoperative when ringing current is projected back over said trunk line.

11. In a telephone system, a party line, a trunk line, an automatic switch for controlling the two, a ring back switch, another line, means for extending the connection either to said ring back switch to signal a station on said party line or to said other line, means for supplying current for talking 30 purposes to said party line, a relay in said trunk line energized thereover for maintaining said automatic switch in operated position independent of said party line, a polarized relay in said trunk line, means 35 controlled by said polarized relay for increasing the supply of talking current to said party line, another relay controlled by said first relay for rendering said polarized relay ineffective to increase the current supply.

40 12. In a telephone system, a party line, a trunk line, an automatic switch for connecting the two, a ring back switch, another line, means for extending the connection 45 either to said ring back switch to signal a station on said party line or to said other line, means for supplying current for talking purposes to said party line, a relay in said trunk line energized thereover for 50 maintaining said automatic switch in operated position independent of said party line, a polarized relay in said trunk line, means controlled by said polarized relay for increasing the supply of talking current to 55 said party line, another relay controlled by said first relay for rendering said polarized 60 party line, another relay controlled by said first relay for rendering said polarized

relay ineffective to increase the current supply, and circuits for each of said relays including a conductor of said trunk line.

13. In a telephone system, a party line, a 65 trunk line, an automatic switch for connecting the two, a ring back switch, another line, means for extending the connection either to said ring back switch to signal a station on said party line or to said other 70 line, means for supplying current for talking purposes to said party line, a relay in said trunk line energized thereover for maintaining said automatic switch in operated position independent of said party line, 75 a polarized relay in said trunk line, means controlled by said polarized relay for increasing the supply of talking current to said party line, another relay controlled by said first relay for rendering said polarized 80 relay ineffective to increase the current supply, a circuit for said first relay and said polarized relay including the two conductors of said trunk line in series, and the circuit of said last relay including only one 85 conductor of said trunk line.

14. In a telephone system a main exchange, a branch exchange, subscribers in each exchange, means for extending a call from a subscriber in the branch exchange to 90 either a subscriber in the main exchange or to another subscriber in the branch exchange, and for supplying battery for talking purposes to the subscriber in the branch exchange, and means automatically operated 95 only when the call is extended to the main exchange for increasing the talking current to the subscriber in the branch exchange.

15. In a telephone system, a party line, other lines, means for extending a call from 100 a subscriber on the party line to another subscriber on his own line or to one of said other lines and for establishing a flow of talking current in the calling line, and a relay operated automatically only when a call 105 is to one of said other lines, for increasing said flow of talking current.

16. In a telephone system, a party line, means for extending a talking circuit from 110 said party line and for establishing a flow of talking current in said talking circuit, means for reversing the flow of current in said talking circuit and a relay responsive to said reversal for increasing the flow of current in said talking circuit, and additional means for rendering said relay ineffective to increase the talking current when battery is reversed.

Signed by me at Chicago, Cook county, Illinois, this 4th day of December, 1917.

TALBOT G. MARTIN.
